UNITED STATES PATENT OFFICE

C. F. THEODOR STEINWAY, OF NEW YORK. N. Y.

PANEL FOR UPRIGHT PIANOS.

SPECIFICATION forming part of Letters Patent No. 315,447, dated April 7, 1885.

Application filed March 26, 1884. (No model.)

To all whom it may concern:

Be it known that I, C. F. THEODOR STEINWAY, of the city, county, and State of New York, have invented certain new and useful 5 Improvements in Panels for Upright Pianos, of which the following is a specification.

The panels used heretofore in upright pianos were either made entirely closed, which prevented the sounds from the strings to pass 10 to the outside, or they were made of ornamental fretwork, which was liable to crack in course of time, owing to the shrinkage of the wood.

The object of my invention is to furnish 15 panels for upright and other pianos, organs, &c., which not alone permit the sound to escape freely, but which may be brought out in any desired design, plain and in relief, so as to extend thereby the scope of ornamentation 20 applicable to the panels of the different kinds of pianos.

In the accompanying drawings, Figure 1 represents a perspective view of an upright piano-forte with my improved panels. Fig. 25 2 is a detail front view of my improved panel on a larger scale; and Fig. 3 is a horizontal section of the same on line *x x*, Fig. 2.

Similar letters of reference indicate corresponding parts.

30 Referring to the drawings, A represents the exterior frame of my improved panel for upright and other piano-fortes, organs, &c., which is composed of two parts, *a* and *b*. This panel may be located at the upper or 35 lower part of the case. The exterior part of the frame A is made of suitable wood, in keeping with the wood from which the case of the piano has been made. A lining or backing, B, of wire-gauze, is clamped between the two 40 parts of the frame A of the panel, the face side of the lining B being covered with open-work filling C, of a suitable plastic material—such as hard rubber, imitation wood, &c.—which is applied to the wire-gauze lining B by 45 a suitable layer of cement, the connection being re-enforced by a second layer of cement at the back of the lining, which acts in the nature of an anchoring on the wire-gauze, so as to retain the open-work filling securely in 50 position. The wire-gauze lining B and the open-work filling C permit the free escape of the sounds, and permit a more artistic treatment of the panels, as the designer is not confined to the heavy continuous lines of the fret-

work, which latter has to be self-supporting 55 and rigid, and does not permit the application of such delicate and fine-lined figures as can be produced by my improved construction. As the filling is cemented or anchored by its entire back surface to the wire gauze 60 it is supported thereon in such a manner that no rattling noise is caused by the passage of the sound-waves through the openings of the panel.

Upon the open-work filling C are cast the 65 ornamental figures or designs, which may be differently colored or not, to suit the fancy. The filling forms a secure backing firmly reinforced by the wire-gauze, and the ornaments are cast upon the face thereof. The latter need 70 not necessarily be of a size sufficiently large to artistically fill the panel, for the filling C presents a neat appearance, and relieves monotony.

Having thus described my invention, I claim 75 as new and desire to secure by Letters Patent—

1. As an article of manufacture, a panel for musical instruments consisting of a frame of two parts, a backing of wire-gauze stretched in said frame and clamped between said parts, 80 and open-work filling of plastic material cemented to said backing of wire-gauze, substantially as described.

2. A panel for the case of piano-fortes, organs, &c., composed of an exterior frame, a lining or backing of wire-gauze, an open-work filling of plastic material cemented to said 85 backing of wire-gauze, and ornamental figures integral with and cast in relief upon said open-work filling, substantially as described. 90

3. A panel for the case of piano-fortes, organs, &c., composed of an exterior frame, a lining or backing of wire-gauze, an open-work filling of plastic material cemented to said 95 backing of wire-gauze, a layer or coating of cement applied to the back of said gauze for anchoring said filling in cemented position, and ornamental figures integral with and cast in relief upon said open-work filling, substantially as described. 100

In testimony that I claim the foregoing as my invention I have signed my name in the presence of two subscribing witnesses.

C. F. THEODOR STEINWAY.
